UNITED STATES PATENT OFFICE.

CHARLES F. WALDRON, OF BOSTON, MASSACHUSETTS.

DESIGN FOR AN ACTOR'S SHIELD.

SPECIFICATION forming part of Design No. 15,013, dated May 20, 1884.

Application filed October 27, 1883. Term of patent 14 years.

To all whom it may concern:

Be it known that I, CHARLES F. WALDRON, a citizen of the United States, residing at Boston, in the county of Suffolk and State of Massachusetts, have invented and produced a new and original Design for Actors' Shields; and I do hereby declare that the same is fully described in the following specification and illustrated in the accompanying drawings.

10 The object of my design is to provide, for the use of actors on the stage or members of secret societies, a most effective shield; and its characteristic feature is the large number of reflectors distributed over its surface, to reflect in many directions the brilliant lights thrown upon it.

15 In the drawings, Figure 1 represents in plan and Fig. 2 in section a shield embodying my design, and made of a sheet or disk, *a*, of suitable material, having a generally-convex face,

and formed with numerous shallow concavities, *c*, each set at a slightly different angle from the others. The effect of this is far beyond anything attainable by plain or smooth armor. A conical horn, *b*, defines the center of the 25 disk and adds to the effect.

I claim as new—

1. The design for an actor's shield herein shown and described, consisting of the convex disk *a*, formed with numerous concave reflectors, *c*, as set forth.
2. The design for an actor's shield herein shown and described, consisting of the disk *a*, horn *b*, and reflectors *c*, as set forth.

In testimony whereof I hereto affix my signature in presence of two witnesses.

CHARLES F. WALDRON.
